UNITED STATES PATENT OFFICE.

ALEXANDER H. PICKEL, OF CARPENTERSVILLE, INDIANA.

CAR-COUPING.

SPECIFICATION forming part of Letters Patent No. 259,204, dated June 6, 1882.

Application filed March 31, 1882. (No model.)

To all whom it may concern:

Be it known that I, ALEXANDER H. PICKEL, of Carpentersville, in the county of Putnam and State of Indiana, have invented certain new and useful Improvements in Car-Couplings; and I do hereby declare that the following is a full, clear, and exact description of the invention, which will enable others skilled in the art to which it appertains to make and use the same, reference being had to the accompanying drawings, which form a part of this specification.

This invention has for its object to produce a simple, inexpensive, and efficient automatic coupling for railroad-cars; and to this end it consists in certain improvements in the construction and operation of the same, substantially as will be hereinafter more fully described, and particularly pointed out in the claim.

In the drawings, Figure 1 is an end view of a car having my improved coupling; Fig. 2, a side view of the draw-head; Fig. 3, a vertical longitudinal sectional view thereof; Fig. 4, a cross-section on the line $\alpha\alpha$, Fig. 2; Fig. 5, a horizontal sectional view on the line $\gamma\gamma$, Fig. 1; and Fig. 6, a perspective view of the various links used in connection with my improved coupling.

Referring by letter to the drawings, A designates the draw-head, in which is formed the usual mouth, B, and link recess or chamber, C.

D is a transverse shaft, having its bearings E E in the top of the draw-head, in which latter is provided a longitudinal slot, F, in which works the coupling-pin G, which is rigidly but removably fixed to shaft D. The slot F is continued some distance forward of shaft D, so that the coupling-pin may be thrown back out of the draw-head, as shown in dotted lines, Fig. 2 of the drawings, when it is not desired to effect a coupling. The lower rear end of the coupling-pin G is formed semicircular, as shown at H, and the pin holds the transverse shaft in position. When, however, the pin is loosened on the shaft the latter may be withdrawn from the draw-head.

On the end of shaft D, outside the draw-head, is fixed an outwardly and rearwardly curved lever, I, which can be operated from

the ground without going between the cars, 50 and may be connected with the top of the car by a chain, J.

K is a forwardly-inclined longitudinal groove formed in the bottom of recess C, which is engaged by the end of the coupling-pin, and prevents lateral strain on the latter, and L is a plate fitted transversely in the bottom of the recess C, directly in front of groove K, to prevent wear at that point, and form a bearing 55 for the link when in position. The front edge, 60 M, of plate L is beveled forwardly, as shown, and the rear edge, N, is beveled rearwardly.

O designates an improved link to be used in connection with my improved coupling. Its square ends P P are beveled, and formed semi-circular at their inner sides, Q Q.

R is the usual link, made bow shape, as shown, for convenience in coupling cars of different heights.

The operation and advantages of my invention will be readily understood.

The link enters the draw-head and pushes the pin upwardly, so that the link can pass in rear of it. The pin then, by its gravity and weight of the lever, falls down and effects the 75 coupling. To uncouple it is only necessary to raise the lever, causing the coupling-pin to be elevated, when the link can be withdrawn from the draw-head.

Having thus described my invention, I claim 80 and desire to secure by Letters Patent of the United States—

The combination, with the draw-head having slot F and provided in its bottom with the transverse plate L, having its front and rear 85 edges, M N, beveled downwardly, as shown, of the transverse shaft D, on which is rigidly but removably fixed the coupling-pin G, having the outwardly and rearwardly curved lever I, as shown, and for the purpose specified. 90

In testimony that I claim the foregoing as my own I have hereto affixed my signature in presence of two witnesses.

ALEXANDER H. PICKEL.
